APPARATUS FOR EXTINGUISHING FOREST FIRES

John Raleigh, Peshtigo, Wis.

Application March 2, 1936, Serial No. 66,682

2 Claims. (Cl. 37—189)

This invention appertains to fire fighting apparatus, and more particularly to a novel method and means for extinguishing forest fires.

Generally, forest fires start from a single point and travel in a narrow lane rapidly from said point in the direction of the wind. This burning lane then less rapidly broadens out laterally in both directions.

Due to the inaccessibility of water in forests, other methods than fighting the fire with water have to be resorted to. Generally, lanes are dug in an effort to cut off the fire. Due to brush, timber, etc., the use of power machinery for this purpose is practically useless.

It is, therefore, one of the primary objects of my invention to provide a light portable device which can be easily handled and manipulated by a single person in a forest to effectively bring about the controlling of a fire therein.

Another salient object of my invention is to provide a portable device, which can be readily manipulated alongside the fire, embodying a rotary digging member for loosening and throwing dirt, sand, and the like from the ground onto the burning brush, etc., to effectively smother and put out the fire.

A further object of my invention is to provide means for digging up sand and the like from the ground and for throwing the same with considerable force against the fire.

A further important object of my invention is the provision of means whereby the machine can be easily guided and tilted, so that the sand or dirt can be directed rather high onto the burning bushes, etc., or straight out on a fire burning close to the ground.

Another further object of my invention is the provision of means for associating different types of rotary diggers with the machine, whereby more or less sand or dirt can be supplied to the fan blower according to the character of the fire being fought.

A further object of my invention is the provision of novel means for suspending and carrying a light portable internal combustion engine from the back of a person for operating various appliances, such as a fire fighting device.

A still further object of my invention is to provide a fire fighting apparatus of the above character, which will be durable and efficient in use, one that is simple and easy to manufacture, and one which can be placed upon the market at a reasonable cost.

With these and other objects in view, the invention consists in the novel construction, ar-

angement, and formation of parts, as will be hereinafter more specifically described, claimed, and illustrated, in the accompanying drawings, in which drawings:

Figure 1 is a complete view showing my improved device in use. 5

Figure 2 is an enlarged, detail, fragmentary side elevation of the bottom part of my improved device, with parts thereof broken away and in section to illustrate structural details. 10

Figure 3 is a horizontal section taken substantially on the line 3—3 of Figure 2, looking in the direction of the arrows. 15

Figure 4 is a side elevation illustrating a modified form of digger associated with the driving shaft and fan. 20

Figure 5 is a detail section taken substantially on the line 5—5 of Figure 4, looking in the direction of the arrows. 25

Figure 6 is a section similar to Figure 5, but taken on the line 6—6 of Figure 4. 30

Figure 7 is a front elevation of my novel back-strap for carrying the internal combustion engine. 35

Figure 8 is a fragmentary detail view illustrating another form of means for holding the protecting hood in place. 40

Referring to the drawings in detail, wherein similar reference characters designate corresponding parts throughout the several views, the letter A generally indicates my improved forest fire fighting apparatus, which comprises a light portable hand device for digging up and spraying sand, dirt, and the like against the burning brush. 45

This light portable hand device includes a substantially vertically disposed tubular supporting casing 10, which rotatably carries the main drive shaft 11. Suitable anti-friction bearings can be interposed between the casing and the shaft, and the upper end of the shaft is adapted to have detachably coupled thereto a flexible drive shaft 12, which can be driven from the crank-shaft 13 of a light portable internal combustion engine 14. 50

Rigidly connected to the lower end of the casing 10 by means of a collar 15 and brackets 16, is a depending hood or thrower casing 17 having an outlet 18 at its periphery. The drive shaft 11 extends through the hood or thrower casing 17, and is adapted to have connected therewith the thrower fan 19 and a digger 20. 55

The fan 19 is arranged above the digger 20 and in the hood or thrower casing 17, and this fan can be secured to the shaft 11 in any desired manner. In the present instance, I have shown 60

the fan to include outwardly extending blades 21 formed on or secured to a collar 22, which is attached to the lower end of the shaft 11 by means of a bolt 23.

5 The digger 20, as shown in Figures 1, 2, and 3, is in the nature of an auger, and the shank of the digger is connected to the shaft in any preferred manner. In the drawings, which represent only one example of my device, the upper 10 end of the auger carries a tang 24, which can be received in a socket formed in the lower end of the shaft, and the bolt 23 can be utilized for holding the tang in position.

Firmly connected with the tubular casing 10 15 is a manipulating handle 25, which can be provided with hand grips 26 and 27 for the operator. The lower end of the handle 25 is pivotally connected to the casing 10 adjacent to its lower end by means of a pivot bolt 28, and the handle 20 has slidably mounted thereon a cuff 29. This cuff is in turn pivotally connected to the casing 10 adjacent to its upper end by means of a link 30.

The link 30 has its opposite ends pivotally 25 connected to the cuff 29 and the casing 10 by means of bolts 31 and 32. The cuff is held in an adjusted position on the handle 29 by means of a set screw or the like 33.

Obviously, by shifting the cuff 29 longitudinally 30 of the handle, the angular position of the handle can be varied with respect to the casing 10, and thus the handle can be disposed at the most advantageous position best suited for the operator.

35 The engine 14 is adapted to be carried on the back of the operator, and I have devised a novel back-strap 34 for this purpose. This back-strap 34 embodies a main shoulder strap 35, which extends over the left-hand shoulder of the operator and under the right-hand armpit. Suitable pads can be utilized to cushion the main strap on the back of the wearer. One end of the main strap 35 carries a loop 36, which is disposed on the chest of the wearer, and the other end 45 of the main strap carries a snap hook 37, which is adapted to be fastened to the loop. Sewed or otherwise rigidly secured to the main strap is a supplemental strap 38, which is adapted to extend under the left-hand armpit of the operator, and this strap is adapted to be connected to the loop 36 by means of a snap hook 39. That portion of the strap 35 directly in rear of the right-hand armpit of the operator carries an eye or loop 40 to which is suspended, by means 50 of a suitable coupling 41, the motor 14. Thus, the motor is carried on the rear right-hand side of the operator, and the flexible drive shaft 12 extends forwardly and downwardly from the engine.

60 Great stress is laid on the method of carrying the engine, as the engine can be utilized when in this position for driving various other types of devices than fire fighting equipment.

In use of my invention, the engine is hung on 65 the back of the operator in the manner set forth, and the flexible drive shaft 12 is connected to the main shaft 11, and the engine is started in the usual manner. The hand grips are firmly grasped by the operator, and the auger 20 is urged into the ground.

70 The rotation of the auger will dig up sand, dirt, and the like, and carry the dirt into the hood 17, where the same is caught by the re-

volving blades 21 and thrown out the opening 18 with considerable force on the fire.

Obviously, the tool can be tilted from one side or the other in order to effectively control the path of the sand and the like thrown out the opening 18, and thus the sand and the like can be directed onto high or low-burning fires.

With my apparatus, I am enabled to quickly check and bring forest fires under control with a minimum amount of effort on the part of an 10 operator.

Obviously, various changes can be made from the broad example shown and described, and different types of diggers can be employed other than the auger 20.

15 In Figures 4, 5, and 6, I have illustrated another type of digger, which is adapted to supply a relatively large quantity of sand and the like to the fan blades and hood.

This digger consists of radially extending blades 20 20 having their outer edges tapered downwardly and curved in opposite directions, as at 41. The lower ends of the blades are of a substantially fishtail bit shape.

In use of the device with this type of digger, 25 the blades are forced into the ground by the operator and the curved edges 41 will rapidly bite into the ground and carrying a relatively great quantity of sand and dirt to the thrower blades.

30 It is to be noted that the collar 15 is secured in place by a set screw 15'. By loosening the set screw 15' the collar 15 and the hood 17 can be turned so that the outlet opening 18 can be disposed at any desired point around the fan 19.

35 As shown in Figure 8, I can utilize a collar of the spleen type, and the sections of the collar can carry ears. These ears can be joined by bolts or screws. This permits the collar to be taken apart for ease in assembling. In 40 some instances, the hood 17 can be raised above the fan or taken off entirely, so that the fan can throw the dirt and sand in all directions.

Other changes in details may be made without departing from the spirit or the scope of my invention, but what I claim as new is:

1. In a device for fighting forest fires, a support, a manipulating handle, means adjustably connecting the handle to the support, a longitudinally extending drive shaft rotatably carried 50 by the support and extending through the lower end thereof, a hood rigidly connected to the support, a rotary earth digging member detachably connected to the shaft below the hood, a fan connected to the shaft and disposed in the hood 55 and above the digger, said hood having an outlet, power means for driving the shaft, said power means including an internal combustion engine, and means for suspending the internal combustion engine from the back of the operator. 60

2. A portable hand tool for fighting forest fires comprising, a sleeve, a longitudinally extending drive shaft rotatably carried by the sleeve and extending through the lower end thereof, a hood 65 non-rotatably connected to the sleeve, a rotary earth-digging member connected to the shaft below the hood, a fan connected to the shaft and disposed in the hood above the digger, said hood having an outlet, means for driving the shaft, and a manipulating and carrying handle secured 70 to the sleeve and extending at an angle thereto. 65
